United States Patent Office

Des. 210,654

Patented Apr. 2, 1968

210,654

STORM DOOR

Abraham Jesse Ivanhoe, Tenafly, N.J., assignor to Win-Chek Industries, Inc., Moonachie, N.J., a corporation of New Jersey

Filed July 19, 1967, Ser. No. 7,886

Term of patent 14 years

(Cl. D13—1)

FIG.1.

FIG.3.

FIG.2.

I claim:

The ornamental design for a storm door, as shown.
